Chas. W. Kirby.

Design for Croquet Balls & Mallets.

DESIGN NO 2845.

PATENTED DEC. 3 1867.

United States Patent Office.

CHARLES WRIGHT KIRBY, OF NEW YORK, N. Y.

Design No. 2,845, dated December 3, 1867.

DESIGN FOR DECORATING CROQUET-BALLS AND MALLETS.

The Schedule referred to in these Letters Patent and making part of the same.

Be it known that I, CHARLES WRIGHT KIRBY, of the city, county, and State of New York, have originated and designed a new Design for Decorating or Ornamenting Croquet-Balls and Mallets, so as to clearly indicate the sides and the order of playing.

As the balls and mallets now are made, eight colors are used upon the starting-posts, to indicate the order of play, and eight corresponding colors are used upon the balls and mallets. The impossibility of obtaining eight different colors, so marked as to be readily distinguishable after they have become dingy by use, and the uncertainty arising in consequence, cause constant confusion in playing.

My invention consists in painting, enamelling, or otherwise decorating the balls and mallets, so that the two sides will be indicated by two colors, each side having its own. The first side, for example, red, and the second black. The balls and mallets should be painted in stripes, from one to eight stripes each, as represented in the drawing. By decorating them in this way, the players may always know the order in which they are to play, as well as the side to which they respectively belong. Instead of this, the balls and mallets may be painted all over, those of each side their own color, as first side red, second side black, and striped all of one color; but the order designated by the number of stripes, from one to eight. Numerals may be substituted for the stripes in either of these.

What I claim as my invention, and desire to secure by Letters Patent, is—

The design for ornamenting croquet-balls and mallets, herein set forth and shown.

CHAS. WRIGHT KIRBY.
